MOSES S. MARSHALL, OF SOMERVILLE, AND JOSEPH G. BICKNELL, OF CAMBRIDGE, MASSACHUSETTS, ASSIGNORS TO THEMSELVES, JOHN T. FOLSOM, AND JOHN S. FOLSOM; SAID MARSHALL ASSIGNOR TO SAID JOHN T. AND JOHN S. FOLSOM.

Letters Patent No. 86,770, dated February 9, 1869.

IMPROVEMENT IN CARRIAGE-BRAKE.

The Schedule referred to in these Letters Patent and making part of the same.

To all whom it may concern:

Be it known that we, MOSES S. MARSHALL, of Somerville, and JOSEPH G. BICKNELL, of Cambridge, both in the county of Middlesex, and State of Massachusetts, have invented certain new and useful Improvements in Carriage-Brakes, of which the following is a full, clear, and exact description, reference being had to the accompanying drawings, making part of this specification, in which—

Figure 1 is a plan or top view.

Figure 2, a vertical transverse section on the line A B of fig. 1.

Figure 3, a longitudinal vertical section on the line Y Z of fig. 1.

Figure 4, a side elevation, and

Figure 5, an end view of the forward portion shown in figs. 1, 3, and 4.

This invention consists—

First, in the use and application of sliding socket-brakes, A, to that portion of the stationary axle, B, of a carriage, cart, or other similar vehicle, just inside the wheel-hubs; and when the annular socket-portions, C, of such brakes extend outward, and encircle the inner ends of the hubs D, which are tapering, and fit and fill the interior of the sliding sockets when brought together; and when the sliding socket-brakes are connected and operated by arms E, and a central sliding plate or rod, F, as clearly shown in the drawings.

Second, this invention consists in the employment of a transverse shaft, G, supported by stands a, and provided with a pin, e, to engage with the end of the sliding plate F, and a lever, H, to turn the shaft G, and operate the slide F in one direction, to apply the brakes to the hubs of the wheels, while a spiral spring, I, acting against a stud, n, projecting from the slide F, operates the slide in the opposite direction, to liberate the brakes, when desired.

Third, our invention consists of a longitudinal sliding plate or rod, J, provided with a ratchet-rack, g, with which a spring or other catch, c, engages. One end of the plate or rod J connects with the lever H, which operates the shaft G and sliding plate F, to apply the brakes to the hubs of the wheels; and the catch c and ratchet-rack hold the plate J and the lever H forward, and retain the brakes in action; and said brakes are released from action, to allow the wheels to turn, by pressing on the stud b, the lower end of which is connected with the spring-catch c, which pressing-action disengages the latter from the rack g, and allows the spiral spring I to throw the plate F forward, and liberate the brakes from the hubs, D, of the wheels.

Fourth, our invention consists of a transverse swinging lever, K, which is pivoted to a support, z, beneath the sliding plate J, when combined with an operating-

lever, L, and connected with the sliding plate F by a pin, h, for operating the latter and the arms E, to apply the brakes to the wheels; and the lower notched end of a latch, d, which swings on a screw or pin, i, in the side rail M, catches on the edge of the lever K, and holds the brakes in action; and said brakes are released from action by pressing on the rounded top, 4, of the latch d, which liberates the opposite end of the latch from the lever K, and allows the spiral spring I to act, as before.

The outer end of the lever K may have a step, m, connected by a stud, p, which will be a convenience in getting into or out of the vehicle.

The lever L may be pivoted to the side rail M, or to any other suitable support convenient for operation.

The last-described operating-devices are intended to be used on express and other large and heavy wagons, but the first-described operating-devices, viz, the shaft G, lever H, plate J, and rack g, are intended for light vehicles, for which such parts may be best adapted.

In all cases, the sliding brakes A, arms E, and the plate or rod F are intended to be substantially as shown and described.

It will be observed that the slide F is slotted at y, to allow of sufficient sliding on screws n.

It will also be observed that the arms E connect with the sliding brakes A by pins v, to operate the same; and the top plates N of the brakes are slotted, and work on screws or guide-pins O, to insure their certain action longitudinally with the axle B.

A second lever, H, may be applied to shaft G, to extend forward beyond the dasher, or front part, of the carriage.

The spring 3, which actuates the catch c, is seen in figs. 1 and 3, and is fastened, at 2, to one of the cross-plates k, which support the longitudinal bar 5, on which the plate J slides, when operated by the lever H.

The spiral spring I may be enclosed in a mortise in the perch P, or secured to the under side thereof.

When the first-described operating-devices are applied to a wagon or other vehicle, the brakes may be applied to the hubs of the wheels to the desired degree when the carriage is in motion, or fully applied when the carriage is stopped, and the wheels secured until ready to start again.

The first part or operation of applying the brake is performed by placing the foot on the plate J, and moving it forward, which operates the lever H, the shaft G, and the pin e, the slide F, and arms E, and applies the brakes to the hubs of the wheels.

To release the brakes from active pressure on the top of the stud b, liberate the catch c from the rack g, and the spiral spring I throws the plate F forward, and liberates the brakes from the hubs D.

When the last-described operating-devices are applied to a wagon, as shown and described, the brakes are applied by drawing the top end of the lever L back, as indicated by an arrow in fig. 3, which throws the outer end of the swinging lever K forward, and the opposite end and the slide F backward; and, by means of the united action of the arms E, pressing outward, the socket-brakes are brought into action with the tapering ends of the hubs D, as before described; and, in the use of the last-named devices, the brakes are released from action by pressing on the top of the rounded end, 4, of the latch d, which liberates the lower or notched end thereof from the edge of the lever L, when the spiral spring I throws the slide F forward, causing the arm E to draw the socket-brakes inward, which releases the hubs D, and allows the wheels to turn freely.

Both of the operating-devices may be applied to the same vehicle, and both operated together or separately; and, if one portion or set of devices should get broken or deranged, the other set or portion of operating-devices will be sufficient to control the brakes and prevent any liability to accident.

The lever K may be operated, to apply the brakes to the wheel-hubs, by the foot of the person in the carriage, applied to the rear side, f, of the outer end of the said lever, and by pushing in a forward direction.

The object of this invention is to hold, or partially hold, the wheels of a wagon, or other vehicle, when descending an incline, or on level ground, when the

horse, or other animal, is shy or unmanageable, and to hold the wheels of the vehicle when left alone, with or without the horse attached.

Having fully described our invention,

What we claim as new, and desire to secure by Letters Patent, is—

1. The socket-brakes A, the axle B, and wheel-hub D, in combination with the arms E and slide F, in the manner and for the purpose substantially as described.

2. The shaft G, pin e, and lever H, in combination with the slide F, arms E, and socket-brakes A, in the manner and for the purpose substantially as described.

3. The plate J, ratchet-rack g, catch e, spring 3, and stud b, when combined and arranged to operate substantially as and for the purpose described.

4. The levers L and K, and latch d, in combination with the slide F, arms E, and socket-brakes A, in the manner and for the purpose substantially as described.

5. The spring I, for operating the slide F, when releasing the brakes from the hubs of the wheels.

6. The combination of all the operative parts herein described, arranged to operate substantially as and for the purpose set forth.

MOSES S. MARSHALL.
JOSEPH G. BICKNELL.
